(57) **CLAIM**

The ornamental design for the combination digging device and head rest, as shown and described herein.

DESCRIPTION

FIG. 1 is an elevated, perspective view of the combination digging device and head rest in a first configuration in accordance with my invention;

FIG. 2 is a front view thereof;

FIG. 3 is a back view of FIG. 1;

FIG. 4 is a side view of FIG. 1;

FIG. 5 is an opposite side view of FIG. 4;

FIG. 6 is a top view of FIG. 1;

FIG. 7 is a bottom view of FIG. 1;

FIG. 8 is an elevated, perspective view of the combination digging device and head rest in a second configuration;

FIG. 9 is a front view of FIG. 8;

FIG. 10 is a back view of FIG. 8;

FIG. 11 is a side view of FIG. 8;

FIG. 12 is an opposite side view of FIG. 11;

FIG. 13 is a top view of FIG. 8; and,

FIG. 14 is a bottom view of FIG. 8.
